PRESS FOR MAKING WAX PATTERNS

Clarence R. Perkins, Tacoma, Wash.

Application June 24, 1936, Serial No. 87,005

8 Claims. (Cl. 18—5.7)

This invention relates to devices for making the wax pattern from which a plaster mold may be made, said mold being used for casting the gold backings to be attached to the bridge on which 5 artificial teeth are removably secured. The characteristic of this gold backing is that it has a vertical ridge in its center which acts as a key to receive and hold the artificial tooth, said key entering a previously formed complementary slot 10 on the rear face of the said tooth. It is therefore necessary that the wax pattern be of the same shape and form as the gold backing and it must, therefore, have the corresponding vertical rib in its face. 15 The object of my invention is to provide means for pressing the wax pattern from a sheet or wad of wax and simultaneously forming thereon the said vertical ridge. It is obvious that, though the wax may be pressed into the desired form by 20 simple pressure of the wax between suitable molds, the said molds cannot be vertically separated without damaging or tearing away the said ridge in the wax and, therefore, it is an object of my invention to provide means whereby the molds 25 can be pressed together to form the desired wax pattern and may then be slid horizontally, relative to each other, to permit the key ridge on the wax pattern to slide out of the slot in the mold, and thereby release the wax pattern from the 30 mold having the slot therein.

The invention further comprises means whereby the mold carriers are hinged together to permit a relative vertical movement; means to lock them in this hinged relation; and means to release them from such hinged relation and to permit only a relative limited sliding movement. 35

I attain these and other objects by the devices and arrangements illustrated in the accompanying drawing, in which—

40 Fig. 1 is a side view of my improved wax pattern press, showing the parts in the positions occupied thereby when the wax is being pressed;

Fig. 2 is a similar view of a portion thereof, showing one mold slid away from the other to release the pattern; 45

Fig. 3 is a side elevation of the upper member of the press, showing it in relation to the pivot pin when it has been slid backward, and showing a portion broken away to reveal its construction; 50

Fig. 4 is an end view of the shank of the upper mold;

Fig. 5 is a side view of the said upper mold, removed from the press;

55 Fig. 6 is a bottom view thereof;

Fig. 7 is an enlarged front view of the said upper mold;

Fig. 8 is a side elevation of the pivot pin; and Fig. 9 is an enlarged front view of the lower mold.

Similar numerals of reference refer to similar parts throughout the several views.

The press comprises two main members, the lower or base member 1 being adapted to be secured to a suitable table or support, if desired, 10 and carrying the lower mold, while the upper member 2 is hingedly secured to the said base member 1 and carries the upper mold.

The base member 1 is provided with two upward extending ears 3 at its rear, and the upper member 2 is provided with a tongue 4 which fits between the said ears 3. A pivot pin 5 passes horizontally and transversely through the said ears 3 and tongue 4, and is provided with a handle 6 at one end. This pin 5 has a portion 7 of its intermediate part flattened as shown in Fig. 8. A suitable washer 8 is screwed on to the end opposite to the said handle 6 to hold the pin in place. This pivot pin 5 passes through a hole in the two ears 3 and may be manually turned therein. The tongue 4 of the upper member 2 of the press, is provided with a horizontal slot 9, said slot being just wide enough to permit the flattened portion 7 of the pin 5 to pass freely therein, and being provided at its rear end with a circular enlargement 10 wherein the pin 5 may freely turn and whereby, when said pin is within said enlargement, the upper member 2 of the press may be freely turned as on a hinge. 20

Thus it will be seen that, when the upper member 2 is pulled forward, as in Fig. 1, so that the pin 5 lies within the enlargement 10 of the slot 9, and when the pin 5 has been turned into the position shown in Fig. 1 wherein the handle 6 thereof and the flattened part 7 are vertical, the said upper member 2 may be raised or lowered to open or close the space between the molds carried by the two members 1 and 2; and when the pin 5 has been turned as shown in Figs. 2 and 3, so that the handle 6 and the flattened part 1 are horizontal, the upper member 2 may be slid horizontally rearward, said part 7 of the pin then lying in the narrower portion of the slot 9, as shown in Figs. 2 and 3, thus removing the upper mold horizontally from the lower mold. It will also be seen that, in the first position, the upper member 2 is locked against all motion except that about the axis of the pin 5, since the pin fits the enlargement 10; and that, in the second position, in which the pin 5 has entered the narrow slot 55

9, the upper member 2 is locked against any movement except horizontally and longitudinally.

The base member 1 of the press is provided with an anvil 11, having a dove-tailed transverse slot 12 in its upper face, said slot 12 being adapted to receive the adjustable carrier 13 on which the mold 14 is secured. The position of the carrier 13 in the slot 12 is adjustably secured by means of the screw 15; thus the mold 14 may be adjusted laterally. The mold 14 is hollowed slightly on its upper face to receive the wax wad and to hold the wax pattern after it has been pressed.

The upper member 2 of the press is provided with an enlargement through which a vertical hole 16 passes, the axis of said hole being in line with the axis of the anvil 11 when the said upper member 2 is in its forward position, shown in Fig. 1. A screw-threaded shank 17 passes freely through the said hole 16 and carries at its lower end the upper anvil 18 of the press. This shank 17 is prevented from turning on its axis by means of a screw 19 in the upper member 2 engaging a vertical slot 20 made in the said shank 17. The vertical position of the anvil 18 is adjusted by means of a lock nut 21 screwed on the shank 17 and engaging the lower face of the upper member 2, and by a thumb nut 22 which is screwed downward on the said shank and engages the upper face of the said upper member 2, thus clamping the said upper member 2 between the two nuts 21 and 22 and rigidly holding the upper mold in adjusted position thereon. The upper anvil 18 is provided with a longitudinal dove-tailed slot 23 in its lower face, said slot 23 being adapted to receive the adjustable carrier 24, to the lower face of which the upper mold 25 is attached. This upper mold 25 is provided with a flat lower face and with a longitudinal slot 26 in its lower face and extending inward from its front edge, said slot 26 being undercut in the desired form to make the key or ridge of the wax pattern above mentioned. The position of the carrier 24 in the slot 23 is adjustably secured by means of a screw 27 passing through the anvil 18 and engaging the said carrier. Thus it will be seen that the upper mold 26 may be adjusted vertically by suitably turning the nuts 21 and 22, and longitudinally by suitable adjustment in the slot 23. Therefore the two molds 14 and 25 may be brought into proper alignment by the longitudinal adjustment of the upper mold and the transverse adjustment of the lower mold.

My apparatus is used in the following manner, the parts being first in the positions shown in Fig. 1:—The upper member 2 is raised and a sheet or wad of wax 28 is placed in the hollow upper face of the lower mold 14, then the upper member 2 is brought down on the said wax and sufficient pressure is applied thereto to cause the wax to enter the slot 26 in the upper mold to form the wax ridge or key 29 and to conform with the shape of the lower mold. Then the handle 6 is turned downward into the horizontal position shown in Fig. 2 and the upper member 2 is slid rearward so that the mold 25 is slid off of the top of the wax 28, the key 29, formed on the wax during the pressure operation, passes out of the slot 26. The wax pattern, thus formed, may then be removed from the mold 14 and is ready for use to form the plaster mold in which the gold backing is to be cast.

It is, of course, understood that many variations of the above described apparatus may be made without departing from the spirit of my invention, as outlined in the appended claims, and that all equivalents of the elements thereof are to be included in the interpretation thereof. 5

Having, therefore, described my invention, what I claim and desire to secure by Letters Patent, is:—

1. An apparatus for molding wax patterns, comprising a base member; a lower mold carried thereby; an upper member; an upper mold carried thereby; means for hingedly securing the two said members together; means for releasing said members from said hinged relation; and 10 means for guiding said upper member in a relative horizontal longitudinal sliding movement between said members when said hinge means is released.

2. An apparatus as set forth in claim 1, wherein in said lower mold is mounted in a transverse slot in said base member, and is transversely adjustable therein.

3. An apparatus for molding wax patterns, comprising a base member; a lower mold carried thereby; an upper member; an anvil carried by said upper member; an upper mold carried thereby; means for hingedly securing the two said members together; means for releasing said members from said hinged relation; and means 25 for guiding said upper member in a relative horizontal longitudinal sliding movement between said members when said hinge means is released.

4. An apparatus as set forth in claim 3, wherein in said upper mold is mounted in a longitudinal slot in said anvil, and is longitudinally adjustable therein.

5. An apparatus as set forth in claim 3, wherein in said upper and lower molds are relatively 40 transversely and longitudinally adjustable.

6. An apparatus as set forth in claim 3, wherein in said anvil is mounted on a vertical shank clamped to said upper member and is vertically 45 adjustable thereon.

7. An apparatus as set forth in claim 3, wherein in said means for hingedly securing said two members together comprises a pair of vertical parallel ears on said base members, a tongue on said upper member mounted between said ears, and a pin passing through said ears and tongue. 50

8. An apparatus for molding wax patterns, comprising a base member; a lower mold carried thereby; an upper member; an upper mold carried thereby; a pair of vertical parallel ears on said base member; a tongue on said upper member mounted between said ears; a narrow slot in said tongue; a circular enlargement of said slot at one end thereof; and a horizontal pin 55 passing through said ears and fitting said enlargement and adapted to act as a pivot whereon said upper member may turn to vertically separate said molds, said pin being manually turnable in said ears and being flattened to permit it to 60 relatively move in the narrow slot when thus manually turned, whereby said upper member may be slid horizontally relatively to the base member.
